UNITED STATES PATENT OFFICE.

SOLON S. JACKMAN, OF SYCAMORE, ILLINOIS.

GRAIN-BINDER.

SPECIFICATION forming part of Letters Patent No. 249,182, dated November 8, 1881.

Application filed December 9, 1878.

To all whom it may concern:

Be it known that I, SOLON S. JACKMAN, of Sycamore, De Kalb county, State of Illinois, have invented new and useful Improvements 5 in Grain-Binders, of which the following is a full description, reference being had to the accompanying drawings, consisting of four sheets, in which—

Figure 1 is a top or plan view of the band 10 or rope forming mechanism, one of the spindles or spools being partly broken away and in section; Fig. 2, a vertical longitudinal section with the gear-wheels removed; Fig. 3, a face view of the band or rope forming devices; Fig. 4, an end view of the spindle or spool; Fig. 5, a side elevation, partly in section, of the spindle or spool, showing also the stationary disk and devices in section; Fig. 6, a face 15 view of the stationary disk and devices; Fig. 7, a detail showing the arrangement of the driving-gear; Fig. 8, a face view of the revolving disk or plate; Fig. 9, a side elevation of the same; Fig. 10, a rear view of the stationary disk; Fig. 11, a top or plan view 20 showing the device attached to a harvester-frame; Fig. 12 a cross-section on line *x x* of Fig. 11; Fig. 13, a detail of the sheaf-holding tongs.

This invention relates to that class of automatic grain-binders commonly known as 30 "straw-binders," where the bundle or sheaf is bound by means of a band or rope the strands of which are taken directly from the straw of the sheaf or bundle, the band or straw rope being formed and wound around the outside 35 of the bundle by suitable mechanism.

In this style of binding as heretofore practiced it has been found necessary to secure the ends of the straw bands or ropes to prevent 40 them from untwisting when released from the binding mechanism, and in practice such untwisting has been found a great objection to the use of automatic grain-binders of this description.

The object of my invention is to overcome 45 this difficulty and to improve the construction and operation of the binding mechanism; and its nature consists in providing devices for making the rope or band which revolve around 50 a common center, but do not rotate on their own axes; in providing a circular head-plate with openings which cut away portions of its

periphery, so as to leave points for stopping the entrance of the grain or fibers at the proper time; in locating in such openings disks 55 which do not rotate on their own axes; in providing the revolving head and non-rotating disks with openings so arranged relative to each other as to regulate the amount of straw taken up for a strand of the band or rope; in 60 providing a spring-latch located in the opening in each disk for preventing the straw in the opening from passing out readily and preventing the twisting of the same; in providing a projecting point to assist in forcing the straw 65 into the opening; in providing a stationary pinion, intermediate idlers, and pinions operating the disk spindles or shafts for giving the required movement to the parts; in providing the spindles or shafts with incasing conical 70 spools to prevent winding of the straw upon the shafts and to free the spools from straw which may be wound around them, and in the several parts and combination of parts hereinafter set forth as new.

In the drawings, *A* represents the bearing; *A'*, the stationary collar or flange; *A''*, the stand or attaching plate; *B*, the main shaft; *C*, the elliptical plate or support for the gear-wheels and other parts; *D*, the arms or bows 80 connecting the plate *C* and the head; *E*, the circular head-plate; *E'*, the inclined surfaces; *F*, the conical-shaped spools; *F'*, the bell-mouth or opening; *F''*, the flat under surfaces or portions of the spools; *G*, the disk-spindles; *H*, 85 the short shafts or rods; *H'*, the bearings for *H*; *I*, the idlers; *I'*, the pinions; *J*, the stationary pinion; *K*, the circular non-rotating disks; *K'*, the opening in the disks *K*; *K''*, the openings in the head *E*; *L*, the spring-latch; *L'*, the 90 spring; *M*, the gathering-arm; *N*, the curved guard-plates; *O*, the sills or lower frame of a harvester; *P*, the sheaf-holding tongs; *a*, the oil-holes in *A*; *b*, a spline on the end of the shaft *B* for a pulley or other driving-wheel; *c* 95 *d*, the universal joint; *f*, the head of the spindle *G*; *f'*, the attaching-screws; *g*, the pivots for the latches *L*; *h*, the points of the latches; *i*, the point of attaching the springs to the latches; *j*, the guard-plate for the end of the latch; *k*, the point on the lower face of the disks; *l*, the triangular projection for crowding the strand into the opening; *m*, the curved gathering-point of the arm *M*; *n n'*, the open-

ings in the head and disks for the passage of the strand; o , the point for shutting off the passage of the straw into the opening; o' , the points formed by the openings n ; p , the flange on the end of the spools F ; q , the cut-away or flat portion of the spools F .

Only the sills O or lower portion of a harvester-frame are shown. The balance of the machine may be of any suitable construction, 10 operating in the usual manner, the grain being delivered to the holding-tongs P by revolving disks and a revolving apron, or in any other suitable manner, the tongs being rotated and opened and closed by any suitable mechanism.

15 The shaft B has its bearing in the cap or support A , having suitable holes, a , for oiling the shaft, and secured to the frame-work O by the stand or plate A'' and suitable bolts. This shaft is to be driven by means of a pulley or 20 gear-wheel, from the main or drive wheel of the harvester, the outer end of the shaft projecting beyond its bearing a sufficient distance for this purpose. The inner end of this shaft passes through the collar or flange A' , which 25 is formed with or permanently secured to the plate A'' . To said shaft is rigidly secured the plate or support C , which plate carries the driving-gear and supports the head E , the head being connected with the plate by the bars or 30 arms D and revolving with the plate and shaft B . This plate or head E is of a circular form, and is preferably depressed at the center, so as to form two inclined surfaces, E' , as shown in Figs. 1, 3, 8, and 9. In these faces E' are 35 large circular openings K'' , so located as to cut away a portion of the periphery of the head E in each side, so as to leave points o o' , between which is an opening, n , as shown in Figs. 3 and 8. In these openings K'' are located the disks 40 K , each disk being secured to the end of a spindle, G , by the head f , so as to be fast thereon and insure its rotation with said spindle. These shafts or spindles G extend back and are connected by a universal joint, c d e , with 45 the short shafts or rods H , which have their bearings H' in the ends of the plate C , as shown in Fig. 1. The end of each shaft H passes through the plate, and to it is secured a pinion, I' , which meshes with an intermediate idler, I , 50 one for each pinion, and the idlers mesh with the stationary pinion J , secured to the collar A' . The pinions I' and the stationary pinion J contain the same number of cogs or leaves. By this arrangement it will be seen that the 55 devices are attached to the revolving shaft and must revolve with it; but as the central cog-pinion, J , is stationary and contains the same number of cogs as the pinions I' , and the idlers I mesh into both the pinions I' I' and the pinion J , it is evident that the pinions I' I' , while traveling around the center of motion, do not revolve upon their own axes, and as the spindles or rods G H are rigidly secured in the pinions I' and in the disks K , it will follow that 65 the disks K do not revolve upon their axes, but always maintain the same vertical position

relative to that maintained by the stationary wheel or pinion J .

In each disk K is an opening, K' , extending to the periphery of the disk, so as to form a mouth or opening, n' , between the points or projections l h , as shown in Figs. 6 and 10. In these openings, K' are located latches L , each latch being pivoted at one end to the stud or projection g , and extending longitudinally across the opening and having its point h guided and held in position by the plate j , secured to the back of the disk, the lower surface of each latch conforming nearly to the shape of the contiguous surface of the opening K' , as shown in Fig. 10. These latches are pressed down and held by springs L' , one for each latch, one end of the spring being secured at i to the latch, and the other end being coiled around the spindle or rod G and secured to the back 80 of the plate or disk K , so as to enable the latch to yield sufficiently to accommodate an amount of straw necessary for the strand and prevent the strand from being withdrawn too easily.

To the face of each disk K is secured a curved 90 arm, M , the lower end, m , of which projects over the opening n' , and is bent or curved outward, so as to project beyond the periphery of the disk, as shown in Figs. 3 and 6.

The disks K are held in place and prevented 95 from slipping out of their bearings K'' by the guard-plates N , which are secured to the faces of the depressed portions E' by bolts or screws, or in any other suitable manner, a portion of these rings or plates being cut away at the point 100 where the openings n are located, as shown in Fig. 3.

The spindles G are incased in conical spools F , the inner ends of which are secured to the disks K by screws f' , and are provided with 105 a flange, p , extending around their periphery, so as to leave a space between the ends of the spools and the disks to permit the springs L' to operate the latches L . The rear ends of these spools are each provided with a bell-mouth or opening, F' , to allow the universal joint to operate. Their lower faces, at the front end, are cut away, so as to leave a flat surface, F'' , and a beveled portion, q , to prevent the end from covering the opening n' in the disk 115 and interfere with the passage of the strand into the opening. These spools or cones F maintain the same relative position as the disks K in the operation of the parts, and their object is to prevent the straws or fibers of the bundle 120 or sheaf from wrapping around the spindles G and preventing the operation of the rope-maker.

The curved point m gathers the straw for the strand from the bundle, and the point or projection l assists in forcing or carrying such 125 strand into the opening or mouth n' .

The device is to be secured to the harvester-frame at any desired angle that will bring the plate E in such relation to the side of the sheaf held in the tongs P and rotated thereby that 130 the openings n and n' in the plate E and disk K will pass the point of contact with the sheaf

simultaneously, the butt-end of the sheaf being toward the rope-maker.

In operation the plate E, as it revolves in the direction of the arrow, Fig. 3, will cause the 5 curved point *m* to gather a portion of the straw from the adjacent surface of the butt of the bundle or sheaf, and the portion so gathered will pass naturally into the mouth or opening *n'* through the opening *n* until a sufficient 10 amount for the strand has passed through the openings, at which time the point *o* will pass the point *k* and separate the straw inside of the opening *n'* from that outside thereof. The straw thus caught will be carried backward into the opening *n'* by the points *l m*, and forced under the latch *L*, where it will be held firmly by the pressure of the spring *L'*, entirely preventing the strand from twisting, so that each strand is laid with the same portion always up by the 20 action of the disk *K*. When the plate E has performed one-half of a revolution, the opposite disk *K* and its devices will be brought into operation, and gather a strand and form it in the same manner. As the sheaf during 25 such operation is slowly rotated on its axis, a new point of contact is continually presented for each operation of the disks, which operations continue until the rope or band is wound around the bundle, completing the binding of 30 the same as the strands are drawn from the disks. By this arrangement each strand of the rope is laid with the same portion always in the same vertical position, by reason of the non-rotation of the disks *K*, instead of being swept 35 around the rope and presenting the same portion to the center of the rope, as is the common practice of using two or more strands, which, when twisted together, lose their identity. The rope thus formed, not being in any manner 40 twisted, cannot have a tendency to untwist, and consequently needs no fastening at either end to hold it in place, as it is self-holding.

As shown, the rope or band is formed from two strands separate and distinct; but by adding 45 pinions *I'*, idlers *I*, disks *K* and their devices, and connecting spindles or rods *G H*, three or more strands can be used in forming the rope or band.

The form of the device can be changed and 50 perform the operation of producing a band or rope made directly from the straw of the bundle or sheaf, having the strands which compose the same laid around each other, each strand being separate and distinct from the 55 others and not twisted, which result is accomplished by causing the strand-forming devices to revolve around a common center without rotating on their own axes, thus laying the strands around each other without allowing 60 them to twist.

Instead of the pinions *I'*, intermediate idlers, *I*, and stationary pinion *J*, the same end may be accomplished by substituting for the cog-wheels pulleys and belts, or sprocket-wheels 65 and chains, or other devices, if desired, so long as the distinctive feature of carrying sep-

arate strands controlled by non-rotating disks remains.

A plane head, *E*, might be used with parallel spindles or rods *G*, dispensing with the 70 universal joint *c d e*, and placing the pinions *I'* nearer the pinion *J*, and using smaller idlers *I*, placed in an oblique position.

If the straws cling around the smaller portion of the spools *F*, they are easily separated 75 as they pass up the cone.

What I claim as new, and desire to secure by Letters Patent, is—

1. The disks *K*, provided with an opening 80 to receive the strand and revolving around a common center without rotating on their own axes, for keeping the strands in the same vertical position, substantially as and for the purposes specified.

2. The plate *E*, provided with circular openings *K''*, in combination with the disks *K*, for keeping the disks in position, substantially as specified.

3. The non-rotating disks *K*, provided with opening *K'* to receive the strands for the band 90 or rope, in combination with the spring-latch *L*, for keeping the strand from twisting in the opening, substantially as specified.

4. The non-rotating disks *K*, in combination with the spindles *G H*, and an operating mechanism for keeping the disks in the same position relative to the vertical, substantially as 95 and for the purposes specified.

5. The non-rotating disks *K*, spindles or rods *G H*, and a supporting-frame, in combination with the pinions *I'*, intermediate idlers, *I*, and stationary pinion *J*, for revolving the parts around a common center without rotating the pinions on their axes, whereby the disks *K* are held with the same part always 100 vertical, substantially as and for the purposes specified.

6. The plate or head *E*, provided with circular openings *K''*, and openings *n* on its periphery, in combination with the disks *K*, provided with openings *K'*, and mouths or openings *n'*, for regulating the amount of straw grasped for a strand as the openings *n n'* pass 110 the point of contact with the bundle simultaneously, substantially as specified.

7. The plate or head *E*, provided with the openings *n* and points *o*, in combination with the disks *K*, provided with the mouths or openings *n'*, and points *k*, for dividing the straw for the strand from that in the bundle or sheaf, 120 substantially as specified.

8. The curved point *m* and point *l*, in combination with the disk *K*, for forcing the straw for the strand into the mouth *n'* of the opening *K'*, substantially as specified.

9. The combination of a revolving head, *E*, and non-rotating disks *K*, located in the face of the head, with a bundle support or tongs *P*, for presenting the bundle to the rope-forming devices in a proper manner, substantially as 130 specified.

10. The conical spools *F*, in combination

with the spindles G, said spools incasing the spindles o, for preventing the winding of straw in the spindles, and loosening any straws that may wind around the spools, substantially as specified.

11. The combination of the head E, rear plate, C, arms D, and driving-gear I I' J, with the spindles G H and disks K, arranged and operating as described, whereby a rope or band

will be formed having two or more strands so laid around each other without being twisted, and requiring no end fastening, substantially as specified.
